A. RUSH.

JOINT FOR METALLIC SASH AND THE LIKE.
APPLICATION FILED JULY 17, 1915.

1,305,746.

Patented June 3, 1919.

UNITED STATES PATENT OFFICE.

ALBERT RUSH, OF COLUMBUS, OHIO.

JOINT FOR METALLIC SASH AND THE LIKE.

1,305,746.

Specification of Letters Patent. Patented June 3, 1919.

Application filed July 17, 1915. Serial No. 40,517.

To all whom it may concern:

Be it known that I, ALBERT RUSH, a citizen of the United States, residing at Columbus, in the county of Franklin and State of 5 Ohio, have invented a certain new and useful Improvement in Joints for Metallic Sash and the like, of which the following is a specification.

The object of this invention generally is 10 to provide an improved joint for cross bars adapted more especially for use in the manufacture of metallic sash whereby simplicity and economy of manufacture are promoted and increased strength of the joint attained.

15 This object I attain specifically by cutting or notching the head portion and a portion of the web of one of the bars and depressing the head and notching the web of the other bar so that the first described bar can be 20 placed on the second bar with the ends of the head of the first bar where notched superposed thereon and thereby supported on the web of the second bar or as set forth in more detail in the following description.

25 The invention is embodied in the example illustrated in the accompanying drawing and described in the following specification.

In the drawing—

30 Figure 1 is a plan view of a frame containing the invention.

Fig. 2 is an edge view of one of the bar members before application.

Fig. 3 is a similar view of a complementary bar.

35 Fig. 4 is a detail of an outer frame member; and

Fig. 5 is a perspective showing the interlocking of the cross bar members which constitute essentially my invention.

40 The cross bar members are made of right angled T-bars preferably of rolled steel of equal cross section. One of these members, as illustrated in Fig. 2 is cut, punched or formed with a slit or notch 6 of a width

45 about equal to the thickness of the web which bisects the head portion of the T-bar, one edge forming said notch being left with a tongue 7. Before application the bar is flexed at the notch sufficiently to open the 50 same so that the head thereof can be placed over the web of another bar as hereinafter explained.

55 The other cross bar, also of T-form and of the same cross sectional dimensions as the first bar, is rolled or otherwise, wrought to form seats 8 in the opposite sides of the

head portion, its web being perforated at 9 to receive the tongue 7 and notched at 10 to receive the small connecting portion 11 of the web of the bar shown in Fig. 2. The 60 seats 8 are made of a depth about equal to the thickness of the head of the T-bar. In practice the bar, as shown in Fig. 2, is placed down upon the bar, as shown in Fig. 3, so that the connecting portion 11 shall 65 enter the notch 10 and upon the depression of the ends of the bar containing said portion 11, the tongue 7 enters the perforation 10 and the adjacent ends of the T-portion enter the seats 8 on opposite sides of the web. 70

The outer frame bars are provided with 75 seats 12 and perforations 13 and the extremities of the cross bars are provided with tongues, as at 14, to enter said perforations 13 after which they are riveted as shown at 15.

The outer frame bars are shown as of L-form. The depression of the seats in these bars to receive the ends of the heads of the cross bars permits the provision of supports 80 that are each even or in one plane all around for the glass pane.

I have shown a frame for the reception of four lights of glass only but obviously the joints and lights can be indefinitely multiplied.

The form and proportions of the parts can in many respects be varied without departing from the gist of the invention as claimed.

What I claim is—

1. A joint including, in combination, a cross bar of angle form having a transverse slit in its head and web portions, and a second or interlocking cross bar having a bent and depressed head portion to form a seat to 90 receive by superposition the head portion of the first mentioned bar at said slit.

2. A joint including, in combination, a cross bar of angle form slit in its head and web portions and provided with a tongue 7, 100 and a second or interlocking cross bar having a bent and depressed head portion to form a seat to receive by superposition the head portion of the first mentioned bar, and provided with a perforation to receive said 105 tongue.

3. A joint including, in combination, a bar of angle form having a transverse slit extending through its head and a portion of its web, and a second or interlocking cross bar having a notch in the edge of its web to receive the remaining portion of the web be- 110

yond at the aforesaid slit, and a depression in the web portion to form a seat to receive by superposition the web at the end of the slit of the first mentioned bar.

- 5 4. A joint including, in combination, a cross bar of angle form having a transverse slit in its head and web portions and provided with a connecting web portion, a second or interlocking cross bar of angle form
10 notched in its web portion to receive the

aforesaid connecting portion of the first mentioned bar and having a bent and depressed head portion to form a seat to receive by superposition the head portion of the first mentioned bar.

ALBERT RUSH.
